(57) **CLAIM**

The ornamental design for an endoscope sheath with oblique tip, as shown and described.

DESCRIPTION

FIG. 1 is a perspective view of an endoscope sheath with oblique tip showing our new design;

FIG. 2 is a partial enlarged view of the claimed design corresponding to the section shown in FIG. 1;

FIG. 3 is a front view of the endoscope sheath with oblique tip thereof;

FIG. 4 is a back view of the endoscope sheath with oblique tip thereof;

FIG. 5 is a right side view of the endoscope sheath with oblique tip thereof;

FIG. 6 is a left side view of the endoscope sheath with oblique tip thereof;

FIG. 7 is a top view of the endoscope sheath with oblique tip thereof; and,

FIG. 8 is a bottom view of the endoscope sheath with oblique tip thereof.

The dashed broken lines in the drawing depict environmental subject matter only and form no part of the claimed design. The dash-dot-dash lines represent the border for the enlarged partial view and form no part of the claimed design. The endoscope sheath with oblique tip is shown with a symbolic break in its length. The appearance of any portion of the article between the break lines forms no part of the claimed design.
